UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SAFETY PANEL-BOX.

1,306,346.

Specification of Letters Patent. Patented June 10, 1919.

Application filed April 11, 1917. Serial No. 161,354.

To all whom it may concern:

Be it known that I, HUBERT F. KRANTZ, residing at Brooklyn, in the county of Kings and State of New York, have invented certain new and useful Improvements in Safety Panel-Boxes, of which the following is a specification.

This invention relates to a safety shutter adapted for use particularly in connection with panel boxes and the like, the present application being directed to a shutter arrangement which is an improvement over the shutter arrangement shown in my pending application Serial No. 85,852.

The object of the present improvement is to provide a more uniformly effective, and a more practical, arrangement of parts.

A more specific object is to provide means whereby to insure the proper assembly of parts of the device at any and all times, either during manufacture or thereafter.

More specifically stated, an object of the invention is to provide a shutter for safety panel boxes in which, when the guard member, or door, of the panel box is being assembled with the body of the panel box, the shutter will be automatically brought into proper assembly with the door so that the shutter will be operatively connected with the door without necessity for the taking of any precautions to this end on the part of the operator.

A further object is to provide a shutter which will stand in shielding position in case the door is disassembled for any reason.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention:

Figure 1 is a vertical sectional view through a panel box having a shutter arranged therein in accordance with this invention.

Fig. 2 is a vertical transverse view taken

substantially upon the plane of line II—II 55 of Fig. 1, the switch mechanism being omitted for the sake of clearness.

Fig. 3 is a view similar to that shown in Fig. 1, but illustrating the position of the parts with the guard door disassembled and 60 in the process of being assembled, and

Fig. 4 is a detailed perspective view of the shutter.

Referring to the drawings for describing in detail the structure which is shown therein, the reference character L indicates the panel box. This has an opening in its upper wall closed by a guard door 1. A main line contact member 2 is arranged within the box near one end, and a branch line contact 3 70 adjacent the opposite end. A switch blade G is provided for closing circuit between these contact members, and a suitable switch mechanism 4 is provided for operating the switch blade from a position shown in full 75 lines in Fig. 1 to a position shown by the light dotted lines, or vice-versa.

The switch mechanism 4, and the switch blade is preferably, though not necessarily, carried by and movable with the door. A 80 switch operating handle 5 is provided by means of which the mechanism 4 may be operated for manually controlling the switch movements. When the door is closed, no access is provided to the interior of the box 85 and the switch mechanism may be moved at will by means of the handle 5 for opening and closing circuit between the contacts 2 and 3. When the door is opened, the switch mechanism is moved to the position shown by the 90 heavy dotted lines shown in Fig. 1, so as to be entirely free of the contacts 2 and 3, and so as to be easily accessible for repairs, or for other purposes.

Since the main line contact 2 is frequently 95 heavily charged, it is desirable that it be positively protected when the door is open so as to prevent an operator from accidentally coming into engagement therewith, either directly or through the medium of a tool or 100 the like which he may have in hand. To this end, a shutter H is provided. The door is fitted with a bracket 6, having a lug 7 thereon which engages within a runway 8 formed upon the shutter H so as to swing the shutter 105 about the pivots 9 thereof from a position shown in full lines in Fig. 1 to the position shown by the heavy dotted lines.

When the door is closed, the lug 7 bears upon the lower surface portion 10 of the runway 8 and holds the shutter open so that the switch blade is free to operate without obstruction. A spring 11 is provided for urging the shutter upwardly at all times.

When the door is swung open, the lug moves forwardly along the surface 10 toward the pivot 9, and as the door continues 10 to swing, the lug, assisted by the spring, swings the shutter upwardly into the heavy dotted position so that the free edge 12 of the shutter engages against a transverse barrier 13 which is fixed within the box in a 15 position to guard the contact 2 at all times.

Engagement of the edge 12 against the barrier 13 arrests movement both of the barrier and of the door.

The shutter while in this position completes a solid wall transversely within the box, entirely shutting off access to the contact 2 from the opening left by the movement of the door.

It will be noted that the spring 11 incidentally serves as a means for resiliently retaining the door in an open position. The snap-catch 14, which it will be seen engages within a notch 15 of the bracket 6 when the door is swung open, may for this reason be dispensed with in some instances. When the door is again closed, the lug 7 presses against the surface 10 and, overcoming the spring 11, moves the shutter downwardly into its original position.

35 In the event that the door is disassembled, as shown in Fig. 3, the spring 11 will hold the shutter in shielding position. When the door is moved to bring the centers 16 and 17 thereof into alignment for assembling the 40 door with the body of the box, the lug 7 will engage against an upper surface portion 18 of the shutter and will force the shutter downwardly against the tension of the spring 11, the lug 7 meanwhile traveling toward the outer end of the surface 18. As the parts 16 and 17 are brought nearer together, the lug 7 will snap off of the outer 45 end of the surface 18 and will engage against the surface 10 in the position shown by full 50 lines in Fig. 1.

After the parts 16 and 17 have been properly connected, any swinging movement of the door will move the lug along the surface 10 within the runway as above described.

55 It will be apparent that in some instances the surface 18 might be dispensed with, but from a practical viewpoint, the presence of the relatively overhanging part forming the surface 18 is desirable, as it provides a relatively under-surface 19, against which the lug 7 may engage to move the shutter positively into full screening position in the event of the spring 11 becoming weakened from any cause.

65 The precise mechanical details of con-

struction of the shutter are in a measure unimportant, but as illustrated, they consist of a body-member 20, made preferably of insulating material, such as fiber, and opposite-end pieces 21 and 22, made preferably of sheet metal, being fixed to the ends of the part 20 and forming flanelike parts thereon providing the pivot elements 9, by means of which the shutter may be connected to the side walls or other parts of the box. The 70 side member 22 of the shutter is shaped as shown in Fig. 4 so as to provide the runway 8 and the co-operative surfaces 10, 18 and 19, above described.

It will be apparent that the shutter may 80 be wider than illustrated, if desired, so that the transverse barrier 13 may be omitted in some instances. The presence of this barrier, however, is of advantage in that it is a positively fixed element in a close 85 guarding position relatively to the contact 2. The contact 2 is preferably carried on the underside of an insulating block 23, and the barrier 13 is supported at the forward edge 90 of this block by means of one or more brackets 24 engaging the block 23 and the barrier, substantially in the manner illustrated.

There may obviously be any number of contacts 2 or any number of switch mechanisms or switch blades transversely of the 95 box, without altering the description above given. In Fig. 2, two of the contact 2 are illustrated.

As many changes could be made in this construction with departing from the scope 100 of the following claims, it is intended that all matter contained in the above description or shown in the accompanying drawings shall be interpreted as illustratiye only and not in a limiting sense.

Having thus described my invention, what I claim as new and desire to secure by Letters Patent, is:

1. The combination with a panel box or the like having a guard member movable into and out of guarding position, of a shutter arranged within the box for shielding a certain element within the box when the guard member is in non-guarding position, and means normally urging the shutter into 110 shielding position.

2. The combination with a panel box or the like having a guard member movable into and out of guarding position, of a shutter arranged within the box for shielding a certain element within the box when the guard member is in non-guarding position, and a spring engaged between the shutter and a portion of the box to constantly urge the shutter into shielding position.

3. The combination with a panel box or the like having a guard member movable into and out of guarding position, of a shutter arranged within the box for shielding a certain element within the box when the 125

- guard member is in non-guarding position, and means to serve the double purpose of urging the shutter into shielding position and of urging the guard member to non-guarding position. 45
4. The combination with a panel box or the like having a guard member movable into and out of guarding position, of a shutter arranged within the box for shielding a certain element within the box when the guard member is in non-guarding position, a spring connected with the shutter to urge the shutter into shielding position, and means between the shutter and the guard member 50
- 10 whereby the spring serves to resiliently retain the guard member in non-guarding position. 55
5. The combination with a panel box or the like having a guard member movable into and out of guarding position, of a shutter arranged within the box for shielding a certain element within the box when the guard member is in non-guarding position, a part carried by the guard member for operating the shutter, and means whereby said part will automatically move into proper cooperative relation with the shutter when the guard member is being assembled with the remainder of the box structure. 60
- 20 6. The combination with a panel box or the like having a guard member movable into and out of guarding position, of a shutter arranged within the box for shielding a certain element within the box when the guard member is in non-guarding position, a lug carried by the guard member for operating the shutter, the shutter having a runway formed therein to receive said lug, and the runway being open-ended and having one wall extended beyond another wall to facilitate the automatic introduction of the lug into the runway coincident with the assembly of the guard member with the remaining elements of the box. 65
- 25 7. The combination with a panel box or the like having a guard member normally closing an opening into the panel box and said guard member being removably mounted upon the panel box, of a shutter arranged within the panel box movable into and out of position shielding a certain element within the panel box, and means adapted to retain the shutter in shielding position in the event of removal of said guard member. 70
- 30 8. The combination with a panel box or the like having a guard member connected therewith adapted to move into and out of position closing an opening in the panel box, a shutter movably mounted within the panel box, connections whereby movement of the guard member into open and closed positions will move the shutter into shielding and non-shielding positions, said guard member being removably mounted upon the panel box, and means to retain the shutter 75 in shielding position in the event of removal of the guard member. 75
- 35 9. The combination with a panel box or the like having a guard member normally closing an opening into the panel box and said guard member being removably mounted upon the panel box, of a contact arranged within the panel box adjacent to said opening, a shutter also arranged within the box being pivotally mounted to swing into and out of position closing access from said opening to said contact, and means adapted to retain the shutter in shielding position in the event of removal of said guard member. 80

In testimony whereof I affix my signature in the presence of two witnesses.
